BARNEY A. KNUDSON, OF SANTA ANA, CALIFORNIA.

CORE FOR CONCRETE WALLS.

1,414,288.

Specification of Letters Patent. Patented Apr. 25, 1922.

Application filed March 2, 1921. Serial No. 449,145.

To all whom it may concern:

Be it known that I, BARNEY A. KNUDSON, a citizen of the United States, residing at Santa Ana, in the county of Orange and 5 State of California, have invented new and useful Improvements in Cores for Concrete Walls, of which the following is a specification.

It is the object of this invention to provide a core employed in connection with forms for concrete walls, the forms preferably being such as described in my co-pending application Serial No. 404,217, filed August 17, 1920.

15 It is the specific object of the invention to provide a core which may be readily expanded and collapsed, so that after the wall has been formed around the core and between the forms, the core may be readily 20 removed by collapsing the same.

The invention will be readily understood from the following description of the accompanying drawings, in which

Figure 1 is a side elevation showing the 25 method of using the cores in connection with concrete walls.

Fig. 2 is a transverse section showing a core and form in position for use.

Fig. 3 is a longitudinal section through 30 a core.

Fig. 4 is a top plan view of the same partly broken away.

In the drawings I have shown the cores employed in connection with forms for 35 pouring concrete walls, the forms preferably comprising uprights 1 and 2 received against the respective sides of a partially completed wall 3 and supporting upright members 4 extending from one form to the 40 next so as to provide a space into which the concrete forming the wall is poured. The uprights 1 and 2 are preferably clamped in position by means of cross member 5 intermediate of the ends of the uprights and by 45 an upper cross member 6 provided with a turnbuckle 7 for adjusting the same. The longitudinally extending members 4 preferably rest upon lugs 8 and are held in position by catches 9.

50 In order to form hollow spaces within the wall, cores constructed in accordance with the present invention are received in the space between the form members 4. These core members are shown as cylindrical members placed in upright position in the space

between the form members, as clearly shown in Fig. 3. Each of the core members consists of a plate 10 curved upon itself with its ends overlapping as shown at 11-12 in order to provide a cylindrical core construction. A top 13 fits over this core construction and an annular depending flange 14 of the top is bolted as shown at 15 to one end of the plate 10. The top is preferably conical in shape so that any of the plastic material being poured, which may fall upon the same, will readily flow downwardly into the space adapted to receive the plastic material. A handle 16 is provided upon the top so that by twisting the handle 70 the top and the end of plate 10 secured thereto may be shifted with relation to the opposite end 11 of the plate for decreasing the diameter of the cylinder forming the core. By this arrangement the core may be 75 either expanded or contracted in order to permit of its insertion and removal from the wall when formed.

A lock is, preferably, provided for retaining the core construction in expanded position, said locking mechanism comprising a bar 20 adapted to extend diametrically across the opening in the core and having an upwardly extended ear pivoted at 21 just above aligned openings 18 and 19 in the overlapping ends 11 and 12, so that when the bar swings downwardly to a horizontal position the end of the bar beyond the pivot 21 will extend through the openings and the opposite end of the bar will press against 90 the opposite side of the core and expand the core. A pull rod 26 is connected to the free end of the bar 20 and extends upwardly through the top of the core and has a handle upon its upper end for operating 95 the bar 20. When the handle is pulled upwardly the free end of the bar 20 swings upwardly out of engagement with the core and the other end withdraws from the openings 18 and 19 and the core collapses sufficiently to be drawn out of the concrete. The pressure for expanding the core is exerted against the pivot 21 when the bar 20 is pushed downwardly.

Various changes may be made without departing from the spirit of the invention as claimed.

What is claimed is:

A core for concrete walls comprising a plate curved upon itself to a circle with its 110

ends overlapping, a top fitting one end of the curved plate and having an annular depending flange bolted to the opposite side of the circle from the overlapping edges, an 5 operating handle extending upwardly from the top, a bar mounted diametrically across the opening near the lower end of the curved plate, an ear extending from one end of the bar and pivotally connected to the 10 curved plate, there being alined openings through the overlapping portions of the plate near the pivot through which the bar extends when in a horizontal position and the opposite end of the bar being adapted 15 to engage the opposite side of the core and exert pressure upon the pivot to expand the core to its normal position, and a pull rod

connected to the free end of the bar and extending upwardly through the top, so that when the pull rod is operated to raise the 20 free end of the bar and the handle on the top operated rotatably the core is contracted to be removed from the concrete, and so that when the core has been reset the pull rod is pushed downwardly to move the bar 25 to its horizontal position thereby expanding the core and passing the end of the bar through the alined openings to hold the core expanded against the pressure of the concrete. 30

In testimony whereof I have signed my name to this specification.

BARNEY A. KNUDSON.
